United States Patent Office

Des. 215,117
Patented Sept. 2, 1969

215,117

VEHICLE MARKER LIGHT

John F. Stahl, Bridgeport, N.Y., assignor to R. E. Dietz Company, Syracuse, N.Y., a corporation of New York

Filed Oct. 18, 1968, Ser. No. 14,075

Term of patent 14 years

Int. Cl. D26—99; D12—14, 99; D29—99
U.S. Cl. D48—32

FIG. 1

FIG. 2

FIG. 4

FIG. 3

FIGURE 1 is a plan view of a vehicle marker light embodying our new design;

FIGURE 2 is a side elevational view thereof, the other side being a mirror image thereof;

FIGURE 3 is a bottom plan view thereof; and

FIGURE 4 is an end elevational view thereof, the other end being a mirror image thereof.

I claim:

The ornamental design for a vehicle marker light, as shown and described.
